TOILET ARTICLE RETAINER

Leo Straus, New York, N. Y.

Application January 16, 1940, Serial No. 314,055

8 Claims. (Cl. 132—79)

This invention relates to a retainer for a set of men's individual toilet articles, especially for shaving purposes.

It is well known that in many family households the regular toilet medicine chest is so filled with various articles that it is very inconvenient for some men to retain the several shaving-set articles together in any neat or clean condition, with the results that much time is lost in shaving and consequent insanitation ensues. Also, under such circumstances it would be better for the user to have all of the shaving-set articles retained individually and apart from said chest, such individual retainer being also useful in cramped toilet situations.

The principal object of the invention, therefore, is to remedy the above mentioned existing disadvantages, and to provide an individual retainer for a full set of shaving articles, which will be compact, simple, of low cost, conveniently and economically manufacturable, strong, durable, and conveniently and efficiently utilized.

Other objects and advantages will hereinafter appear.

25 In the accompanying drawing,

Fig. 1 shows a general front elevation of the retainer for men's individual toilet articles, constituting the invention.

Fig. 2 is a longitudinal cross-sectional elevation 30 of the retainer, taken on the line 2—2 of Fig. 1.

Fig. 3 is a top plan view of the retainer shown in Fig. 1.

The individual retainer 1 comprises a vertically elongated box-like receptacle 2, which is preferably integral and made of molded material, and having a rear wall 3, a floor 4, side walls 5, 6, a ceiling 7, and an entirely open, accessible front side 8. The floor 4 is provided with a central partition 9, thereby forming together with the walls 40 5, 6 a pair of pockets 10, 11, which are utilized for the retention of fresh and used razor blades, as illustrated. Projecting interiorly of the receptacle 2 from its side-walls 6 is a pair of shelves 12, upon which rests the head 13 of a safety 45 razor 14, the handle 15 of which is suspended vertically directly over the partition 9, and a bracket 16 provided with a recess 17 receives said handle for maintaining it against lateral dislocation, as shown. The exterior of ceiling 7 is formed 50 as a yoke 18, and hence so configurated that it will retain a shaving soap tube 20 in the transverse disposition to the receptacle 2, as illustrated. From the side-wall 5 projects a hook 19 for the suspension therefrom as shown a shaving brush 55 21, and from the wall 6 projects a ring 22 adapted

to receive a tumbler 23, a subsidiary ring 24 forming part of the ring 22 being utilizable for suspension therefrom of a toothbrush 25. Openings 26 provided in rear wall 3 serve for passage of screws therethrough, for thereby fastening the retainer 1 to any wall or convenient body.

It will be evident, therefore, that by resort to the retainer of this invention, the individual may maintain all of his shaving articles together and apart from the regular medicine chest in the toilet room, and hence in sanitary state and utmost convenience for rapid and efficient shaving.

Having thus described my invention, I claim:

1. A retainer for men's individual toilet articles having the combination of a vertically elongated box-like receptacle provided with a rear wall, side walls, a ceiling and a floor, said floor having a central partition wherewith said side walls and rear wall form a pair of pockets for fresh and used razor blades, said receptacle having means for suspending a razor therein directly over said partition, said rear wall having means for attachment of the receptacle, said ceiling having a yoke adapted for retention of a shaving soap tube, one of said side walls having means for retention of a shaving brush, and the other of said side walls having means for retention of a tumbler and tooth brush.

2. A retainer for men's individual toilet articles having the combination of a vertically elongated box-like receptacle provided with a rear wall, side walls, a ceiling, and a floor, said floor having a central partition wherewith said side walls and rear wall form a pair of pockets for fresh and used razor blades, said receptacle having means for suspending a razor therein directly over said partition, and said rear wall having means for attachment of the receptacle.

3. A retainer for men's individual toilet articles having the combination of a vertically elongated box-like receptacle provided with a rear wall, side walls, a ceiling and a floor, said floor having a central partition wherewith said side walls and rear wall form a pair of pockets for fresh and used razor blades, said receptacle having means for suspending a razor therein directly over said partition, said rear wall having means for attachment of the receptacle, and said ceiling having a yoke adapted for retention of a shaving soap tube.

4. A retainer for men's individual toilet articles having the combination of a vertically elongated box-like receptacle provided with a rear wall, side walls, a ceiling and a floor, said floor having a central partition wherewith said

- side walls and rear wall form a pair of pockets for fresh and used razor blades, said receptacle having means for suspending a razor therein directly over said partition, said rear wall having 5 means for attachment of the receptacle, said ceiling having a yoke adapted for retention of a shaving soap tube and one of said side walls having means for retention of a shaving brush.
5. A retainer for men's individual toilet articles having the combination of a vertically 10 elongated box-like receptacle provided with a rear wall, side walls, a ceiling and a floor, said floor having a central partition wherewith said side walls and rear wall form a pair of pockets for fresh and used razor blades, said receptacle 15 having means for suspending a razor therein directly over said partition, said rear wall having means for attachment of the receptacle, and one of said side walls having means for retention of a shaving brush.
6. A retainer for men's individual toilet articles having the combination of a vertically elongated box-like receptacle provided with a rear wall, side walls, a ceiling and a floor, said floor having 20 a central partition wherewith said side walls and rear wall form a pair of pockets for fresh and used razor blades, said receptacle having means for suspending a razor therein directly over said partition, said rear wall having means for attachment of the receptacle, said ceiling having a

yoke adapted for retention of a shaving soap tube, and one of said side walls having means for retention of a tumbler and tooth brush.

7. A retainer for men's individual toilet articles having the combination of a vertically 5 elongated box-like receptacle provided with a rear wall, side walls, a ceiling and a floor, said floor having a central partition wherewith said side walls and rear wall form a pair of pockets for fresh and used razor blades, said receptacle 10 having means for suspending a razor therein directly over said partition, said rear wall having means for attachment of the receptacle, and one of said side walls having means for retention of a tooth brush.

8. A retainer for men's individual toilet articles having the combination of a vertically elongated box-like receptacle provided with a rear wall, side walls, a ceiling and a floor, said floor having a central partition wherewith said 15 side walls and rear wall form a pair of pockets for fresh and used razor blades, said receptacle having means for suspending a razor therein directly over said partition, said rear wall having means for attachment of the receptacle, said 20 ceiling having a yoke adapted for retention of a shaving soap tube, and one of said side walls having means for retention of a tooth brush.
